Patented May 2, 1916.

UNITED STATES PATENT OFFICE.

HARRY A. SCHWARTZ, OF CHICAGO, ILLINOIS.

DENTAL LAMP.

1,181,348.

Specification of Letters Patent.

Patented May 2, 1916.

Application filed June 3, 1915. Serial No. 31,802.

To all whom it may concern:

Be it known that I, HARRY A. SCHWARTZ, a citizen of the United States, residing at Chicago, in the county of Cook and State of Illinois, have invented a certain new and useful Improvement in Dental Lamps, of which the following is a specification.

My invention relates to dental lamps for use of dentists, throat specialists or others desiring to illuminate the mouth of the patient.

The object of my invention is to produce a construction such that the operator may obtain a beam of reflected light in distinction to a direct light, and may readily and instantly throw the beam in the direction desired. In this connection it is my purpose to obtain a construction such that light may be used by either a right handed or left handed operator.

Another object of the invention is to provide a lamp having an external casing which always remains cool to thereby avoid danger or discomfort to the operator and his patient.

Still another object, is to provide, in connection with such a lamp, a mirror for the use of the patient, which mirror may be adjusted to practically every conceivable position which might be necessary for its use.

It is also my object to obtain certain refinements of detail which will be hereinafter more particularly noted.

I obtain my objects by the mechanism illustrated in the accompanying drawings, in which—

Figure 1 is a side elevation of the complete lamp, parts of the casing being removed to better reveal the construction.

Fig. 2 is a front view of the assembled lamp. Fig. 3 is a plan section on the line 3—3, Fig. 1. Fig. 4 is a vertical section on the line 4—4, Fig. 1.

Similar numerals refer to similar parts throughout the several views.

The lamp bulb 1 is preferably a nitrogen electric lamp, the same being capable of throwing a strong and steady light from a comparatively small bulb. This lamp is

mounted upon any suitable socket 2 having a switch 3. The electric conductors may be led to the socket if desired through a flexible tube 4. In the particular design shown, a metallic base 5 rises from the socket 2, said base being of sheet metal and circular in cross-section. Surmounting the base is a

casing consisting, in the particular design selected to illustrate the invention, of an outer and inner shell. In this design the outer shell consists of a lower hemispherical element 6, resting upon the annular upper mouth of the base 5 and having an inwardly projecting annular shoulder 7 for supporting the lower hemispherical portion 8, of the inner shell. The outer and inner shells are completed by the outer and inner hemispherical portions 9 and 10 respectively. These outer and inner shells are not necessarily truly spherical, but are preferably approximately spherical. The outer shell is perforate or foraminous while the inner shell is imperforate, except for the ports 11 near the bottom, as best shown in Fig. 1. These shells are open at the top, the opening being covered by a wire screen 12. As a result of this construction air can pass in through the walls of the outer shell and thus reduce the temperature of the inner shell and keep down the temperature of the outer shell to a point where it will not cause any discomfort to one touching it. The screen 12 at the top, serves as a protector to prevent anything from dropping onto the lamp bulb, and also cuts off some of the light which is thrown upward from the bulb. This reduces the glare which otherwise might annoy the operator. The inner shell has an opening 15 at the front through which the light from the lamp bulb may pass out. Opposite this opening is a collar 16 which is cylindrical and has a horizontal axis which passes approximately through the center of the lamp bulb. Fitting into this collar is a lens holder 17 which carries an external bezel 18 for retaining the lens 19. In this construction the rim of the lens is held against the annular end of the lens holder by the flange 20 of the bezel, the cylindrical sides of the bezel itself surrounding the lens and thus holding it in place. The lens holder is rotatable about its longitudinal axis, being held in the desired position by the screw 21, shown in Fig. 1. The bezel is rotatable upon the lens holder, being held in any desired position by the set screws 22, 22.

A block 25 is pivotally mounted upon bezel 18 so as to rotate about a pin 26 extending transversely to the focal axis of the lens. This block carries a pin 27 which serves as a pivot for the block 28, which serves as a support for a concave reflector.

Said reflector consists, in the present instance, of a concave glass 29, backed up by a metallic backing 30, as best shown in Fig. 3. The pin 27 extends transversely to pin 26 and the result is that the mirror 29, 30 may be moved to various positions—in fact the parts 25, 26, 27 and 28 constitute what may be termed "a universal joint".

A mirror 32 is fastened to a rod 33 which is both slideable and rotatable in an arm 34 pivotally attached by a screw 35 to a clip 36 mounted upon a stem 37 resting in the upright socket 38 as best shown in Fig. 1. The construction of the parts which support the mirror 32 is such that the mirror may be brought to practically any position desired, thus enabling the patient to see into his mouth for the purpose of inspecting the dental work which may have been done, or for any other purpose.

In operation, when the switch 3 is turned on and the lamp bulb is illuminated, it throws a beam of light through the lens 19, which lens, in the preferred construction, is a double convex lens and tends to focus the light. The focal axis is indicated by the broken line *a*, Fig. 3. If the reflector 29, 30 is brought to the position shown in dotted lines in Fig. 3, the beam will be reflected in general along the broken line *b*, Fig. 3. As the reflector is concave, it will tend to concentrate the beam of light, so that under ordinary conditions it will be concentrated to a comparatively small area at that point 35 in the mouth or throat where the operator is working. In other words, the illuminated area or field will be comparatively small, the intensity of light will be correspondingly great. The amount of concentration, however, may be varied by varying the shape of the lens or the concavity of the reflector during the manufacture of the appliance. As the reflector is hinged upon a universal joint it is possible to throw the beam in almost 40 any direction or to throw the reflector back out of the path of the beam as indicated in full lines in Figs. 1, 2 and 3. In case the operator is left handed or occasion may

arise, for any other reason, the position of the reflector may be reversed by rotating the 50 bezel 18 upon the lens holder 17. By rotating the bezel 180° the reflector hinge will occupy a position on the opposite side of the lens. It will thus be manifest that the reflector may be brought to practically any 55 position desired, and the appliance may be used for a variety of purposes. If the mirror 32 is not wanted, the stem 37 may be lifted out of the socket 38 and the entire mirror and its supporting arms taken away. 60

Having thus described my invention, what I claim as new and desire to secure by Letters Patent, is:—

1. A dental lamp having a casing provided with an inner and an outer sheet metal 65 shell approximately spherical in form and concentric, the outer shell having inlet openings in the side, said shells having concentric openings at the top for the escape of heat, and a screen over said openings for 70 the purpose described.

2. In a dental lamp, the combination of a lamp casing having an opening in the side, a lens holder coaxial with said opening, a lens, a bezel for holding said lens in position in the holder, said bezel being rotatable upon the holder about the axis of said holder, a concave reflector, and a universal hinge joint by which said reflector is secured to said bezel. 80

3. In a dental lamp, the combination of a lamp casing having an opening in the side, a lens extending across said opening, holding means on said casing for holding said lens in position, a reflector, and a universal 85 joint connecting said holding means and said reflector for the purpose described.

4. In a dental lamp, the combination of a lamp casing having an opening in the side, a lens extending across said opening, a ring 90 on said casing rotatable about the focal axis of the lens, a reflector and a universal joint connecting said reflector with said ring.

In witness whereof, I have hereunto subscribed my name.

HARRY A. SCHWARTZ.
